METHODS OF MAKING STATIONERY IMPLEMENTS AS PAPER PENCILS

Stanley L. Basche, 6048 N. 12th St., Philadelphia, Pa.

Filed May 12, 1958, Ser. No. 734,744

1 Claim. (Cl. 156—185)

This invention relates to articles of stationery and more particularly to pencils and similar articles having a core with a sheath of paper other flexible material therearound.

It is the principal object of the present invention to provide improved articles of stationery comprising a core with an enclosing casing of rolled paper or the like, and improved methods of making the same by which the manufacture of the article is greatly expedited and simplified.

It is a further object of the present invention to provide improved methods of making articles of stationery, such as paper pencils and the like, in which operations now considered necessary for the production of such articles are eliminated with consequent saving of labor costs.

It is a further object of the present invention to provide improved methods of making articles such as paper pencils and the like by which savings in the amount of paper employed will be effected.

It is a further object of the present invention to provide improved methods of making articles of stationery, such as paper pencils and the like, in which the unpeeling of the end after coloring or imprinting is eliminated.

It is a further object of the present invention to provide methods for the production of articles as aforesaid in which the operation of individual coloring or imprinting, or both, after the product has been formed, are eliminated.

Other objects and advantageous features of the invention will be apparent from the description and claim.

The nature and characteristic features of the invention will be more readily understood from the following description, taken in connection with the accompanying drawings forming part thereof, in which:

FIGURE 1 is a view in elevation of an article of stationery made in accordance with the invention;

FIG. 2 is an enlarged end elevational view as seen from the right of FIG. 1;

FIG. 3 is a plan view of one side face of a paper blank employed in connection with the invention;

FIG. 4 is a fragmentary plan view of the other side face of a portion of the blank shown in FIG. 3, parts being broken away to show the steps and the details of construction;

FIG. 5 is a fragmentary sectional view, enlarged, taken approximately on the line 5—5 of FIG. 4; and

FIG. 5A is a fragmentary sectional view similar to FIG. 5 and showing a modified form of the invention.

It should, of course, be understood that the description and drawings herein are illustrative merely, and that various modifications and changes may be made in the components and steps disclosed without departing from the spirit of the invention.

Like numerals refer to like parts throughout the several views.

In the manufacture of paper pencils and the like, as currently practiced, the raw stock in the form of paper having weakened lines thereon is wrapped around a core with the end secured by an adhesive to retain the shape of the article. The article is then dipped to provide an exterior coating of colored ink or the like. The separate articles are oriented and suitable descriptive indicia are then imprinted on the exterior to identify the maker, the intended use of the article and for other purposes. One end is then sliced transversely to provide a finished

2

end and the other end is unpeeled for a portion of its length and to expose the end of the core for use.

Referring now more particularly to the drawings, the article in finished form includes a core 10, of material selected in accordance with the intended use of the article. The core 10 can be of any desired material such as graphite compositions customarily employed for pencils, crayons of wax compositions and the like, rubber with an included abrasive if the article is to be used as an eraser, or a plurality of strands of hemp, jute, cordage or the like, if the article is to be used for a brush.

The core 10, in the article in finished form, is surrounded by a paper cover 11 wound thereon. In order to provide the cover 11 in accordance with the present invention, a blank 12 is provided, of any suitable grade of paper or similar flexible material commonly employed for articles of this character, and the blank 12 is provided with a plurality of parallel weakened lines 13 to facilitate the subsequent peeling of successive coils to expose additional lengths of the core 10. The blank 12 preferably has provided thereon suitable perforations or depressions 14 spaced inwardly from one side margin 20 thereof which constitutes an outer longitudinally disposed marginal terminal edge portion in the completed article and may be provided initially or during its assembly, on one side face thereof as shown in FIG. 3, with a band or strip 15 of glue or other adhesive. The opposite face of the blank 12, as shown in FIG. 4, and in spaced relation to the perforations or depressions 14 can be provided with a strip or band 16 of color of suitable width to provide a sufficient colored area imprinted or otherwise applied as hereinafter referred to. Where the blank 12 is of paper of a color other than white, the band 16 can be white in color and thus provide an underlay. The width of the band 16, inwardly from the side marginal edge 20 of the blank 12 at which the perforations or depressions 14 are located, is preferably sufficient to cover the last two layers of the circumference of the exterior of the cover 11.

In superposed relation to the band 16 a band 17 is applied, preferably of a different and/or contrasting color from that of the band 16, and to provide the desired color on the finished exterior of the article.

In the application of the band 17 a reverse printing plate, silk screen or stencil may be employed so that simultaneously with the application of the band 17 the desired identifying indicia or legend, indicated at 18, will be apparent on the article. The band 16 can provide a contrasting color visible on the face of the finished article through openings in the band 17 by reason of the reverse plate printing, silk screening or stencilling. The width of the band 17 inwardly from the side marginal edge 20 of the blank 12 at which the perforations or depressions 14 are located is preferably in excess of the circumference of the exterior of the paper cover 11 and preferably to extend onto the outer two plies of the cover 11 so that the color of the band 16 can be seen through perforations or other openings in the outer ply of the cover 11. The continuity of color will thus be unaffected by perforations at 14.

The bands 16 and 17 can be of any suitable material such as an ink with a glossy or dull finish, as desired.

If desired, and as indicated in FIG. 5A, where an extra gloss or lustre is desired, an overlay coating 19 of lacquer, varnish or resin can be applied to the blank 12 subsequent to the application of the band 17. The lacquer, varnish or resin band 19 is, of course, preferably transparent so as to not obscure the color of the band 17.

In accordance with the invention the bands 16 and 17 and the band 19, if used, are applied to the blank 12 on a multicolor press either simultaneously with or separately

from the application of the score lines 13 and prior to the assembly of the articles.

The blank 12, prepared as previously explained and with the colored band or bands providing an imprinted colored area and indicia thereon, is wound onto the core 10 with the score lines 13 helically disposed with respect to the core 10. During the winding operation the adhesive band 15 is employed to engage with the contiguous face portions of the paper cover 11 and prevent unwinding of the blank 12 from the core 10. The end opposite the intended point of the core 10 is then preferably trimmed in the usual manner and the article is ready for use.

It will be noted that by reason of the application of the bands 16 and 17 and/or 19 to the core 10 in the manner previously described, and prior to winding, the cover 11 will have on the exterior thereof a suitable color and identifying indicia for the article visible to the user.

Upon breaking of the point or to expose an additional length of the core 10 for use, one or more coils provided by the score lines 13 are severed and unrolled in the customary manner.

It will also be noted that no costly dipping operations are required, that by reason of the coloring and indicia applied prior to winding a completed article can quickly be made, and the necessity for unpeeling as heretofore required is eliminated, and that the objects of the invention previously stated are attained in a simple and expeditious manner.

I claim:

1. A method of making a stationery implement having a core surrounded by a wound cover of a single sheet of flexible material having an adhesive band on one side thereof for securing the cover, which comprises imprinting a solid band of coloring material on a cover blank along an extending inwardly from one longitudinal marginal edge thereof on the opposite side, said cover having parallel weakened lines thereon extending from said marginal edge, said imprinted band having a width in excess of the circumference of the finished cover in wound condition, and helically winding the core within a plurality of layers of the cover with the marginal edge of the cover exteriorly disposed in secured relation to the cover and with said imprinted band in exposed longitudinally and circumferentially disposed relation and with said marginal edge in partial overlapping relation to said imprinted band.

The method of making a stationery implement having a core surrounded by a wound cover of a single sheet of flexible material having an adhesive band on one side thereof for securing the cover, which comprises imprinting a solid band of coloring material on a cover blank along an extending inwardly from one longitudinal marginal edge thereof on the opposite side, said cover having parallel weakened lines thereon extending from said marginal edge, said imprinted band having a width in excess of the circumference of the finished cover in wound condition, and helically winding the core within a plurality of layers of the cover with the marginal edge of the cover exteriorly disposed in secured relation to the cover and with said imprinted band in exposed longitudinally and circumferentially disposed relation and with said marginal edge in partial overlapping relation to said imprinted band.

UNITED STATES PATENT OFFICE
CERTIFICATE OF CORRECTION

Patent No. 3,010,862

November 28, 1961

Stanley L. Basche

It is hereby certified that error appears in the above numbered patent requiring correction and that the said Letters Patent should read as corrected below.

Column 1, line 10, after "paper" insert -- or --; column 2, line 37, before "depressions" for "of" read -- or --; column 4, line 6, after "along" for "an" read -- and --.

Signed and sealed this 10th day of April 1962.
